(57) **ABSTRACT**

A liquid discharge head includes a channel unit. The channel unit is formed therein with: a plurality of individual channels aligning in a first direction, a common channel extending in the first direction, a supply hole in communication with the common channel, and a damper chamber provided in a position overlapping with the supply hole in a second direction orthogonal to the first direction. The channel unit includes a first plate having a first surface where a recess is formed to constitute the damper chamber, and a second plate having a second surface attached to the first surface via an adhesive. A protrusion is provided on a bottom of such a first part of the recess as overlaps with the supply hole in the second direction.

LIQUID DISCHARGE HEAD AND METHOD FOR MANUFACTURING LIQUID DISCHARGE HEAD

CROSS REFERENCE TO RELATED APPLICATIONS

The present application claims priority from Japanese Patent Application No. 2020-180358, filed on Oct. 28, 2020, the disclosure of which is incorporated herein by reference in its entirety.

BACKGROUND

Description of the Related Art

Conventionally, there are known ink jet heads (liquid discharge heads) where a damper chamber is provided in a position overlapping with an ink supply port (a supply hole). The ink supply port has a larger area than the other flow channel parts. Because the damper chamber is provided in that part of a large area, it is possible to obtain a high damper performance.

SUMMARY

In such an ink jet head as described above, the lower surface of a damper plate where a recess is formed to construct the damper chamber is attached to the upper surface of a spacer plate via an adhesive. For example, the adhesive applied to the outer circumference of an elastic roller and then the roller is pressed on the lower surface of the damper plate while the roller is rotated. By virtue of this, an adhesive applying process is carried out to apply the adhesive to the lower surface of the damper plate and, after the adhesive applying process, an attaching process is carried out to first stack the damper plate and the spacer plate and then attach the upper surface of the spacer plate to the lower surface of the damper plate via the adhesive.

Especially, if the damper chamber (the recess) is large in size, then in the adhesive applying process, the outer circumference of the roller may come into the recess to allow the adhesive to adhere to the bottom of the recess. In such a case, in the attaching process, the bottom surface of the damper chamber (recess) of the damper plate is attached to the upper surface of the spacer plate such that the damper chamber may be sized smaller than desired. Furthermore, because it is possible for the damper chamber to have a difference size from what is desired, it is not possible to obtain a stable damper performance.

Accordingly, an object of the present disclosure is to provide a liquid discharge head capable of obtaining a stable damper performance, and a method of manufacturing the same.

According to an aspect of the present disclosure, there is provided a liquid discharge head including a channel unit. The channel unit includes: a plurality of individual channels, a common channel, a supply hole, and a damper chamber. The plurality of individual channels are aligned in a first direction, each of the individual channels includes a nozzle. The common channel extends in the first direction and is connected to the plurality of individual channels. The supply hole is connected to the common channel. The damper chamber is located at a position overlapping with the supply hole in a second direction orthogonal to the first direction. The channel unit includes a first plate and a second plate. The first plate includes a first surface which is orthogonal to

the second direction and on which a recess forming the damper chamber is formed. The second plate includes a second surface attached to the first surface via an adhesive. A protrusion is located at a bottom of a first part of the recess, the first part of the recess overlapping with the supply hole in the second direction.

BRIEF DESCRIPTION OF THE DRAWINGS

- 10 FIG. 1 is a plan view of a printer 100;
FIG. 2 is an exploded perspective view of the head 1;
FIG. 3 is an enlarged exploded perspective view of the channel unit 10;
15 FIG. 4 is an enlarged cross section view of the head 1 along the line IV-IV of FIG. 2;
FIG. 5 is an enlarged cross section view of the head 1 along the line V-V of FIG. 2;
20 FIG. 6 is a plan view depicting a recess 45x and protrusions 45y provided in a lower surface 13x of a damper plate, and grooves 12y provided in an upper surface of a spacer plate;
FIG. 7A is a cross section view along the line VII-VII of FIG. 6, depicting an adhesive applying process;
25 FIG. 7B is a cross section view along the line VII-VII of FIG. 6, depicting an attaching process;
FIG. 8 is a cross section view of a head 1A corresponding to FIG. 7B; and
30 FIG. 9 is a plan view of a head 1B corresponding to FIG. 6.

DETAILED DESCRIPTION

In the following explanation, the direction Z is a vertical direction, the direction X and the direction Y are horizontal directions. The direction X and the direction Y are both orthogonal to the direction Z. The direction X is orthogonal to the direction Y. The direction Y corresponds to the "first direction" of the present disclosure, the direction Z corresponds to the "second direction" of the present disclosure, and the direction X corresponds to the "third direction" of the present disclosure.

First Embodiment

45 First, referring to FIG. 1, an explanation will be made on an overall configuration of a printer 100 including heads 1 according to a first embodiment of the present disclosure.

The printer 100 is provided with ahead unit 1x including four heads 1, a platen 3, a conveyer 4, and a controller 5.

50 Paper 9 is brought on the upper surface of the platen 3.

The conveyer 4 has two roller pairs 4a and 4b arranged to interpose the platen 3 in the direction X. If the controller 5 controls a conveyance motor (not depicted) to be driven, then the roller pairs 4a and 4b rotate with the paper 9 being nipped therebetween to convey the paper 9 along the direction X.

55 The head unit 1x is of a line type, being elongate in the direction Y to discharge ink onto the paper 9 from nozzles 35 (see FIGS. 2 to 5) with its position being fixed. The four heads 1 are elongate respectively in the direction Y and arrayed zigzag in the direction Y.

60 The controller 5 has a ROM (Read Only Memory), a RAM (Random Access Memory), and an ASIC (Application Specific Integrated Circuit). The ASIC carries out a recording process and the like based on programs stored in the ROM. In the recording process, the controller 5 records image on the paper 9 by controlling a driver IC of each head

and the conveyance motor (all not depicted) on the basis of a recording command (including image data) inputted from an external device such as a PC or the like.

Next, referring to FIGS. 2 to 6, a configuration of the head 1 will be explained.

The head 1 has, as depicted in FIG. 2, a channel unit 10, a filter member 20, and an actuator member 60.

The channel unit 10 includes eight plates in total: a nozzle plate 11, a spacer plate 12, a damper plate 13, manifold plates 14a and 14b, spacer plates 15 and 16, and a cavity plate 17. Those eight plates are made of metal, resin, ceramic and the like, respectively, and stacked on and attached to each other via an adhesive in the direction Z. The damper plate 13 corresponds to the "first plate" of the present disclosure, and the spacer plate 12 corresponds to the "second plate" of the present disclosure.

In the nozzle plate 11, five nozzle arrays are formed. The five nozzle arrays align in the direction X. Each nozzle array includes a plurality of nozzles 35 aligning in the direction Y. The plurality of nozzles 35 are formed of a plurality of through holes arrayed zigzag in the direction Y.

In the cavity plate 17, five pressure chamber arrays are formed. The five pressure chamber arrays align in the direction X. Each pressure chamber array includes a plurality of pressure chambers 36 aligning in the direction Y. The plurality of pressure chambers 36 are formed of, in the same manner as the nozzles 35, a plurality of through holes arrayed zigzag in the direction Y.

The pressure chambers 36 are in respective communication with the nozzles 35 via through holes 37 formed through the spacer plates 15 and 16, the manifold plates 14a and 14b, the damper plate 13, and the spacer plate 12. Further, each pressure chamber 36 is in communication with one corresponding common channel 7 among five common channels 7 via a communication hole 38 formed in the spacer plate 16 and a connection flow channel 40 formed in the spacer plate 15 (see FIGS. 2 to 4).

In the channel unit 10, five individual channels are formed. The five individual channels align in the direction X. Each individual channel includes a plurality of individual channels 30 aligning in the direction Y. Each individual channel 30 is formed to reach to the nozzle 35 through the connection flow channel 40, the communication hole 38, the pressure chamber 36, and the through hole 37. In the same manner as the nozzles 35 and the pressure chambers 36, the plurality of individual channels 30 are arrayed zigzag in the direction Y.

In the manifold plates 14a and 14b, through holes are formed to construct the five common channels 7. The five common channels 7 extend respectively in the direction Y and align in the direction X. The five common channels 7 are in respective communication with the five individual channel arrays. Each common channel 7 is in communication with a plurality of individual channels 30 belonging to the corresponding individual channel array among the five individual channel arrays.

The upper surface of the damper plate 13 defines the bottom of the five common channels 7. In the lower surface 13x of the damper plate 13, a recess 45x is formed to define a damper chamber 45 (see FIGS. 2 to 4). Because the damper chamber 45 (the recess 45x) overlaps with the five common channels 7 in the direction Z, even if a pressure arises in the pressure chamber 36 and transmits to the common channel 7 in an ink discharge from the nozzle 35, the pressure is attenuated by an elastic deformation of the bottom (thin film) of the recess 45x in the damper plate 13.

By virtue of this, it is possible to prevent the phenomenon of the pressure's transmission to another pressure chamber 36 (a so-called crosstalk).

A plurality of protrusions 45y are provided on the bottom 5 of the recess 45x in the lower surface 13x (the first surface) of the damper plate 13. Further, a plurality of grooves 12y are provided in such a part of the upper surface 12x of the spacer plate 12 (the second surface) as overlaps in the direction Z with the respective protrusions 45y. Details of 10 that will be explained later on.

As depicted in FIG. 2, at the ends of the cavity plate 17 and the spacer plates 15 and 16 on one side in the direction Y, four through holes are formed to construct the supply holes 47 respectively. The supply holes 47 align in the 15 direction X. Each supply hole 47 is constructed from a supply hole 47a for supplying the black ink, a supply hole 47b for supplying the yellow ink, a supply hole 47c for supplying the magenta ink, and a supply hole 47d for 20 supplying the cyan ink, in this order from the left according to FIG. 2.

The first and second two common channels 7a from the left in FIG. 2 are in communication with the supply hole 47a. The third common channel 7b from the left in FIG. 2 25 is in communication with the supply hole 47b. The fourth common channel 7c from the left in FIG. 2 is in communication with the supply hole 47c. The fifth common channel 7d from the left in FIG. 2 is in communication with the supply hole 47d. The supply holes 47a, 47b, 47c and 47d 30 overlap respectively with the ends of the common channels 7a, 7b, 7c and 7d at one side in the direction Z.

Each of the supply holes 47b, 47c, and 47d where the color inks are supplied is in communication with one of the common channels 7b, 7c, and 7d whereas the supply holes 35 47a are in communication with the two common channels 7a where the black ink is supplied. This is because when the recording speed is raised to be higher in monochromatic recording than in color recording, it is considered that the black ink is consumed more in quantity per unit time than 40 any color ink per unit time.

The filter member 20 is attached to the upper surface of the channel unit 10 (the upper surface of the cavity plate 17) via an adhesive to cover the four supply holes 47. The filter member 20 includes four filters 20a, 20b, 20c, and 20d 45 overlapping respectively with the supply holes 47a, 47b, 47c, and 47d in the direction Z. The respective color inks supplied from an ink tank (not depicted) flow into the supply holes 47a, 47b, 47c, and 47d after foreign substances (dusts and the like) are removed in passing through the filters 20a, 20b, 20c, and 20d, to supply the common channels 7a, 7b, 7c, and 7d. In this manner, the filters 20a, 20b, 20c, and 20d 50 constructing the inflow ports of the supply holes 47a, 47b, 47c, and 47d are provided at the upper side of the supply holes 47a, 47b, 47c, and 47d (at the other side than the damper chambers 45 in the direction Z).

The actuator member 60 is attached to such an area via an adhesive as without the filter member 20 being arranged on the upper surface of the channel unit 10 (the upper surface of the cavity plate 17). Detailed illustration being omitted, 60 the actuator member 60 includes a vibration plate, a common electrode, a plurality of piezoelectric bodies, and a plurality of individual electrodes 61. The vibration plate and the common electrode are arranged on the upper surface of the channel unit 10 (the upper surface of the cavity plate 17), to cover all pressure chambers 36 formed in the cavity plate 17. On the other hand, the piezoelectric bodies and the individual electrodes 61 are provided according to each 65

pressure chamber 36 to overlap respectively with the pressure chambers 36 in the direction Z.

A wiring member 70 (see FIG. 4) is arranged on the upper surface of the actuator member 60. The wiring member 70 has wires connected electrically with the respective individual electrodes 61 and the common electrode.

The controller 5 (see FIG. 1) controls a driver IC mounted on the wiring member 70 to maintain the potential of the common electrode at the ground potential and to change the potential of the individual electrodes 61 between a driver potential and the ground potential. On this occasion, in the vibration plate and the piezoelectric bodies, the parts interposed between the individual electrodes 61 and the pressure chambers 36 deform to project toward the pressure chambers 36. By virtue of this, the pressure chambers 3 change in volume such that a pressure is applied to the inks in the pressure chambers 36 to discharge the inks from the nozzles 35.

Next, referring to FIGS. 2, 5 and 6, an explanation will be made on the recess 45x and the protrusions 45y provided in the lower surface 13x of the damper plate 13, and the grooves 12y provided in the upper surface 12x of the spacer plate 12.

The recess 45x can be formed by way of half-etching the lower surface 13x of the damper plate 13. The protrusions 45y are formed without etching the parts corresponding to the protrusions 45y during that half etching. The grooves 12y can be formed by way of half-etching the upper surface 12x of the spacer plate 12.

As depicted in FIG. 2, the recesses 45x include four first parts P1 overlapping respectively with the four supply holes 47 in the direction Z, and five second parts P2 overlapping respectively with the five common channels 7 but not overlapping with the supply holes 47 in the direction Z. A width W1 of each first part P1 (the length in the direction X) is larger than a width W2 of each second part P2 (the length in the direction X).

The protrusions 45y are provided in the first parts P1. In particular, each of the four first parts P1 is provided with three protrusions 45y. The three protrusions 45y are all rectangular and elongate in the direction X on a plane orthogonal to the direction Z, and aligned in the direction Y.

An interval S1 (see FIG. 6) in the direction X between each protrusion 45y and either side wall of the recess 45x (the first part P1) is 1 mm or less. Each protrusion 45y is arranged at the center of the recess 45x (the first part P1) in the direction X for the interval S1 to be constant.

An interval S2 (see FIG. 6) in the direction Y between the protrusion 45y closest to one end of the recess 45x (the first part P1) in the direction Y among the three protrusions 45y, and the side wall of the recess 45x (the first part P1) is 1 mm or less. An interval S3 in the direction Y between one and another of the three protrusions 45y is also 1 mm or less. The three protrusions 45y are arranged at the same intervals S2 and S3 from one end of the recess 45x (the first part P1) in the direction Y.

The groove 12y is provided to correspond to each protrusion 45y to overlap in the direction Z with each protrusion 45y. The groove 12y is rectangular and elongate in the direction X on a plane orthogonal to the direction Z just as with the protrusion 45y. The groove 12y is sized larger than the protrusion 45y but smaller than the recess 45x (the first part P1). That is, the groove 12y includes a part overlapping in the direction Z with the protrusion 45y and a part overlapping in the direction Z with the other part than the protrusion 45y on the bottom of the recess 45x (the first part P1).

As depicted in FIG. 5, the spacer plate 12 is thicker than the damper plate 13 in the direction Z (for example, the spacer plate 12 is 100 μm thick whereas the damper plate 13 is 50 μm thick). The recess 45x and the grooves 12y are each as deep as almost half of the thickness of the plates 12 and 13, respectively. That is, a depth D2 of the groove 12y in the direction Z is larger than a depth D1 of the recess 45x in the direction Z. The protrusion 45y is as high as the depth D1 of the recess 45x.

Next, referring to FIGS. 7A and 7B, an explanation will be made on a process of attaching the damper plate 13 and the spacer plate 12.

In this process, a roller 90 depicted in FIG. 7A is used. The roller 90 includes a shaft 90a, and a peripheral part 90b arranged about the shaft 90a. The peripheral part 90b is an elastic member made of urethane (at a density of 1.92×10^{-7} kg/mm³, for example) or the like.

First, as depicted in FIG. 7A, an adhesive A is applied to a peripheral surface 90x of the peripheral part 90b which is rotated about the shaft 90a along the direction X while the peripheral surface 90x is pressed on the lower surface 13x of the damper plate 13. In this manner, the adhesive A is applied to the lower surface 13x (the adhesive applying process). On this occasion, the pressing force is, for example, 500 kPa. Further, the roller 90 is moved at this time in a transference direction T along the direction Y with respect to the lower surface 13x (see FIG. 6). The transference direction T is orthogonal to a direction in which the protrusions 45y extend (the direction X) on a plane orthogonal to the direction Z.

Because of its elasticity, the peripheral part 90b may deform when pressed by the lower surface 13x in the adhesive applying process, to enter the inside of the recess 45x (the first part P1). For example, if the protrusions 45y are not provided on the bottom of the recess 45x (the first part P1), then the peripheral part 90b enters the inside of the recess 45x (the first part P1) such that the adhesive A is more likely to attach to the bottom of the recess 45x (the first part P1). However, in the first embodiment, the protrusions 45y are provided on the bottom of the recess 45x (the first part P1), and the interval S1 is narrowed (S1 < W1). By virtue of this, the adhesive A is less likely to attach to the bottom of the recess 45x (the first part P1). On the other hand, because the leading end surfaces of the protrusions 45y are positioned below the bottom of the recess 45x (the first part P1) (at the same level as the lower surface 13x in the first embodiment), the adhesive A applied to the peripheral surface 90x attaches thereto (see FIG. 7B).

Next, after the adhesive applying process depicted in FIG. 7A, as depicted in FIG. 7B, the damper plate 13 and the spacer plate 12 are stacked together such that the upper surface 12x of the spacer plate 12 is attached to the lower surface 13x of the damper plate 13 via the adhesive A (the attaching process). On this occasion, between the damper plate 13 and the spacer plate 12, the damper chamber 45 is formed. Especially, in the part of overlapping with the supply hole 47 in the direction Z (see FIG. 2), because the groove 12y is provided in the upper surface 12x of the spacer plate 12, the protrusion 45y is not attached to the upper surface 12x such that the damper chamber 45 is formed to include the space between the protrusion 45y and the groove 12y.

Note that as in the first embodiment, the configuration of not attaching the protrusion 45y to the upper surface 12x is applicable to the case of, for example, the ink viscosity being 2 to 5 cps, and the drive frequency being 25 to 30 kHz.

As described above, according to the first embodiment, the protrusion **45y** is provided on the bottom of the recess **45x** (the first part P1) constituting the damper chamber **45**. In this case, in the adhesive applying process (FIG. 7A), the adhesive A is more likely to attach to the leading end surface of the protrusion **45y**. Further, the adhesive A is less likely to attach to the other parts than the protrusion **45y** on the bottom of the recess **45x** (the first part P1). By virtue of this, it is possible to prevent the problem that the adhesive A attaches to some unexpected parts such that the damper chamber cannot be formed in a desired size. That is, by intensively providing the protrusion **45y** to which the adhesive A is more likely attach, the adhesive A is thus prevented from being attached to the other parts than the protrusion **45y** in the bottom of the recess **45x** (the first part P1). By virtue of this, it is possible to form the damper chamber **45** in a desired size, thereby allowing for obtaining a stable damper performance.

As depicted in FIG. 2, the recess **45x** includes the first part P1 overlapping with the supply hole **47** in the direction Z, and the second part P2 not overlapping with the supply hole **47** but overlapping with the common channel **7** in the direction Z. The width W1 (the length in the direction X) of the first part P1 is larger than the width W2 (the length in the direction X) of the second part P2. Consider that the protrusions **45y** are not provided on the bottom of the recess **45x** (the first part P1). In such a case, in the adhesive applying process (FIG. 7A), when the roller **90** is moved in the direction Y, the peripheral part **90b** of the roller **90** is more likely to enter the inside of the recess **45x** (the first part P1). Then, this is more likely to give rise especially to a problem that the adhesive A attaches to the bottom of the recess **45x** (the first part P1). In the first embodiment, however, in the case of the width W1 being comparative large in such fashion, by providing the protrusions **45y** on the bottom of the recess **45x** (the first part P1) to narrow the interval S1 (S1<W1). By virtue of this, the adhesive A is made less likely to attach to the bottom of the recess **45x** (the first part P1), thereby preventing the above problem from arising.

At the upper side of the supply hole **47** (the other side than the damper chamber **45** in the direction Z), an inflow port of the supply hole **47** (filters **20a**, **20b**, **20c**, and **20d**) are provided (see FIGS. 2 and 5). In this context, with the ink flowing in from the inflow port, a high pressure arises in the supply hole **47**. However, the damper chamber **45** attenuates that pressure to allow for prevention of undesirable influence on liquid discharges. Further, with the damper chamber **45** which is necessary for attenuating the high pressure in this manner, a stable damper performance is obtainable such that it is possible to realize a high flow amount of the liquid discharges.

The grooves **12y** are provided in the part of the upper surface **12x** of the spacer plate **12** overlapping in the direction Z with the protrusions **45y** (see FIG. 5). In this context, in the attaching process (FIG. 7B), it is possible to let the protrusions **45y** not attach to the spacer plate **12**. By virtue of this, it is possible to secure the size of the damper chamber **45** with the recess **45x** including the protrusions **45y** as a whole, thereby allowing a high damper performance to be obtained.

The depth D2 of the groove **12y** in the direction Z is larger than the depth D1 of the recess **45x** in the direction Z (see FIG. 5). In this context, in the attaching process (FIG. 7B), even if the plates **12** and **13** bend to deform, it is still possible to let the protrusions **45y** not attach to the spacer plate **12**. By virtue of this, it is possible to secure more reliably the

size of the damper chamber **45** with the recess **45x** including the protrusions **45y** as a whole, thereby allowing a high damper performance to be obtained.

The spacer plate **12** is thicker than the damper plate **13** in the direction Z (see FIG. 5). In this context, it is possible to reliably realize a deep structure of the grooves **12y** as described above.

The groove **12y** includes a part overlapping with the protrusion **45y** in the direction Z, and a part overlapping in the direction Z with the other part of the bottom of the recess **45x** (the first part P1) than the protrusion **45y** (see FIG. 6). In this context, in the attaching process (FIG. 7B), even if a positional deviation arises between the plates **12** and **13**, it is still possible to let the protrusions **45y** not attach to the spacer plate **12**. By virtue of this, it is possible to secure reliably the size of the damper chamber **45** with the recess **45x** including the protrusions **45y** as a whole, thereby allowing a high damper performance to be obtained.

A plurality of protrusions **45y** are provided on the bottom of a recess **45x** (see FIG. 6). In this context, it is more reliably to let the adhesive A be less likely to attach to the other part of the bottom of the recess **45x** than the protrusions **45y**. By virtue of this, it is possible to form the damper chamber **45** in a desired size and to obtain a stable damper performance in a reliable manner.

The intervals S1 and S2 between the protrusion **45y** and the side walls of the recess **45x** are 1 mm or less (see FIG. 6). In this context, it is more reliably to let the adhesive A be less likely to attach to the other part of the bottom of the recess **45x** than the protrusions **45y**. By virtue of this, it is possible to form the damper chamber **45** in a desired size and to obtain a stable damper performance in a reliable manner.

The protrusions **45y** are rectangular on the plane orthogonal to the direction Z (see FIG. 6). In this context, it is easy to let the intervals S1 and S2 be constant between the protrusions **45y** and the side walls of the recess **45x**, thereby allowing reliably for realizing the configuration of letting the adhesive A be less likely to attach to the other part of the bottom of the recess **45x** than the protrusions **45y**.

In the adhesive attaching process (FIG. 7A), the roller **90** is moved in a direction orthogonal to the direction X in which the protrusions **45y** extend on the plane orthogonal to the direction Z (the transference direction T: see FIG. 6). In this context, in the contact part between the lower surface **13x** of the damper plate **13** and the peripheral surface **90x** of the roller **90**, there is a smaller interval between the protrusion **45y** and its peripheral part (another protrusion **45y** or the side wall of the recess **45x**). By virtue of this, it is more reliably to let the adhesive A be less likely to attach to the other part of the bottom of the recess **45x** than the protrusions **45y**. By virtue of this, it is possible to form the damper chamber **45** in a desired size and to obtain a stable damper performance in a more reliable manner.

Second Embodiment

Next, referring to FIG. 8, a head **1A** according to a second embodiment of the present disclosure will be explained. Note that any explanation for the same configuration with the head **1** according to the first embodiment will be omitted.

With the head **1** in the first embodiment (FIG. 7B), the groove **12y** is provided in the upper surface **12x** of the spacer plate **12**, such that the protrusion **45y** of the damper plate **13** is not attached to the upper surface **12x**. With the head **1A** in the second embodiment (FIG. 8), however, the groove **12y** is not provided in the upper surface **12x** of the spacer plate

12, such that the protrusion 45y of the damper plate 13 is attached to the upper surface 12x via the adhesive A.

Note that as in the second embodiment, the configuration of the protrusion 45y being attached to the upper surface 12x is applicable to the case of, for example, the ink viscosity being 4 cps, and the drive frequency being 20 to 25 kHz.

According to the second embodiment, by attaching the protrusion 45y to the upper surface 12x of the spacer plate 12, it is possible to form the damper chamber 45 in a desired size and to obtain a stable damper performance.

Third Embodiment

Next, referring to FIG. 9, a head 1B according to a third embodiment of the present disclosure will be explained. Note that any explanation for the same configuration with the head 1 according to the first embodiment will be omitted.

With the head 1 in the first embodiment (FIG. 6), a plurality of protrusions 45y are provided on bottom of the recess 45x (the first part P1). With the head 1B in the third embodiment (FIG. 9), however, one protrusion 45y is provided on the bottom of the recess 45x (the first part P1). Further, in the third embodiment, in the same manner as in the second embodiment (FIG. 8), the groove 12y is not provided in the upper surface 12x of the spacer plate 12, such that the protrusion 45y of the damper plate 13 is attached to the upper surface 12x via the adhesive A.

According to the third embodiment, it is possible to apply the adhesive A reliably to the protrusion 45y (see FIG. 8). In particular, if a plurality of protrusions 45y are provided, then it is possible for the adhesive A to be unapplied to some of the plurality of protrusions 45y. As in the third embodiment, however, if one protrusion 45y is provided, then it is possible to reliably apply the adhesive A to that protrusion 45y. Furthermore, it is possible to attach the protrusion 45y to the upper surface 12x of the spacer plate 12 and to obtain a stable damper performance in a more reliable manner.

Modified Embodiments

The embodiments of the present disclosure were explained hereinabove. However, the present disclosure is not limited to the above embodiments but may be changed and modified in various manners without departing from the true spirit and scope set forth in the appended claims.

The size and position of the protrusions may be determined by the elasticity of the roller peripheral part, the roller pressing force in the adhesive applying process, the necessary damper performance, and the like.

The protrusions are not limited to being rectangular on the plane orthogonal to the second direction, but may be trapezoidal, circular, or the like.

In the first embodiment (FIG. 6), the plurality of protrusions are arrayed in one direction (the direction Y). However, the plurality of protrusions may be arrayed in a matrix form in the second direction.

The leading end surface of the protrusion is not limited to being at the same level as the first surface of the first plate. For example, in the first embodiment (FIG. 5), the height of the protrusion 45y is the same as the depth D1 of the recess 45x, and the leading end surface of the protrusion 45y is at the same level as the lower surface 13x of the damper plate 13. However, without being limited to that, the height of the protrusion 45y may be smaller than the depth D1 of the recess 45x, and the leading end surface of the protrusion 45y may be positioned above the lower surface 13x of the damper plate 13 (closer to the bottom of the recess 45x).

The present disclosure is not limited to the application to printers but may be applied to facsimile apparatuses, photocopier apparatuses, multifunctional apparatuses, and the like. Further, the present disclosure is also applicable to liquid discharge apparatuses used for other purposes than recording images (such as liquid discharge apparatuses discharging an electrically conductive liquid to substrates to form an electrically conductive pattern). Further, the present disclosure is applicable to any apparatuses other than the liquid discharge apparatuses.

What is claimed is:

1. A liquid discharge head comprising:

a channel unit including:

a plurality of individual channels aligned in a first direction, each of the individual channels including a nozzle;
a common channel extending in the first direction and connected to the plurality of individual channels;
a supply hole connected to the common channel; and
a damper chamber located at a position overlapping with the supply hole in a second direction orthogonal to the first direction,
wherein the channel unit includes a first plate and a second plate,
wherein the first plate includes a first surface which is orthogonal to the second direction and on which a recess forming the damper chamber is formed,
wherein the second plate includes a second surface attached to the first surface via an adhesive, and
wherein a protrusion is located at a bottom of a first part of the recess, the first part of the recess overlapping with the supply hole in the second direction.

2. The liquid discharge head according to claim 1, wherein the recess includes the first part, and a second part which is not overlapped with the supply hole and is overlapped with the common channel in the second direction, and

wherein the first part of the recess is longer than the second part in a third direction orthogonal to the first direction and the second direction.

3. The liquid discharge head according to claim 1, wherein an inflow port of the supply hole is located at an end of the supply hole in the second direction, the end being opposite to the damper chamber in the second direction.

4. The liquid discharge head according to claim 1, wherein the second plate includes a groove arranged on the second surface and overlapped with the protrusion in the second direction.

5. The liquid discharge head according to claim 4, wherein the groove is deeper than the recess in the second direction.

6. The liquid discharge head according to claim 5, wherein the second plate is thicker than the first plate in the second direction.

7. The liquid discharge head according to claim 4, wherein the groove includes a first portion overlapping with the protrusion in the second direction, and a second portion overlapping with an area of the bottom other than the protrusion in the second direction.

8. The liquid discharge head according to claim 1, wherein the protrusion is attached to the second surface.

9. The liquid discharge head according to claim 8, wherein the protrusion is located on the bottom of the recess.

10. The liquid discharge head according to claim 1, wherein a plurality of protrusions including the protrusion are located on the bottom of the recess.

11

11. The liquid discharge head according to claim 1, wherein an interval between the protrusion and a side wall of the recess is 1 mm or less.

12. The liquid discharge head according to claim 1, wherein the protrusion is rectangular on a plane orthogonal to the second direction.

13. A method for manufacturing a liquid discharge head, the liquid discharge head comprising:

a channel unit including:

a plurality of individual channels aligned in a first direction, each of the individual channels including 10 a nozzle;

a common channel extending in the first direction and connected to the plurality of individual channels;

a supply hole connected to the common channel; and a damper chamber located at a position overlapping 15 with the supply hole in a second direction orthogonal to the first direction,

wherein the channel unit includes a first plate and a second plate,

wherein the first plate includes a first surface which is 20 orthogonal to the second direction and on which a recess forming the damper chamber is formed,

12

wherein the second plate includes a second surface attached to the first surface via an adhesive, and wherein a protrusion is located at a bottom of a first part of the recess, the first part of the recess overlapping with the supply hole in the second direction, the method for manufacturing the liquid discharge head comprising:

applying an adhesive to the first surface by applying the adhesive to a peripheral surface of an elastic roller and rotating the elastic roller while pressing the peripheral surface on the first surface; and

attaching the second surface to the first surface via the adhesive by stacking the first plate and the second plate after applying the adhesive.

14. The method for manufacturing the liquid discharge head according to claim 13, wherein in applying the adhesive, the elastic roller is moved in a moving direction on a plane orthogonal to the second direction, the moving direction being orthogonal to a direction in which the protrusion extends.
